UNITED STATES PATENT OFFICE.

HALVER RUFUS STRAIGHT, OF ADEL, IOWA.

CLAY-MIXING MACHINE.

1,303,611.

Specification of Letters Patent. Patented May 13, 1919.

Application filed July 3, 1918. Serial No. 243,161.

To all whom it may concern:

Be it known that I, HALVER R. STRAIGHT, a citizen of the United States, and a resident of Adel, in the county of Dallas and State 5 of Iowa, have invented a certain new and useful Clay-Mixing Machine, of which the following is a specification.

The object of my invention is to provide a clay mixing machine having parts so constructed and arranged as to thoroughly and 10 effectively mix clay.

A further object is to provide a machine of simple and relatively inexpensive mechanical construction, including an endless 15 conveyer comprising a plurality of rows or series of rollers having belts or the like mounted thereon, and a flexible endless conveyer member adapted to travel on said belts, the parts being so arranged as to permit the material to drop downwardly 20 between the different rows or series of rollers to a certain degree so as to cause considerable agitation of the material as the material passes over the rollers.

With these and other objects in view, my 25 invention consists in the construction, arrangement and combination of the various parts of my device, whereby the objects contemplated are attained, as hereinafter more 30 fully set forth, pointed out in my claims, and illustrated in the accompanying drawings, in which:

Figure 1 shows a vertical, central, sectional view through a clay mixing machine 35 embodying one form of my invention.

Fig. 2 shows a top or plan view of the same, the water pipe being omitted.

Fig. 3 shows a vertical, transverse, sectional view taken on the line 3—3 of Fig. 2.

Fig. 4 shows a transverse, vertical, sectional view taken on the line 4—4 of Fig. 2, the outer endless canvas or belt being omitted.

Fig. 5 shows a detail, sectional view of a 45 portion of the conveyer in a slightly modified form of my invention.

Fig. 6 shows a similar view of still another form.

In the accompanying drawings I have 50 used the reference numeral 10 to indicate generally the lower supporting members of a frame having the spaced, longitudinally arranged frame members 12. The frame

members 12 are connected and braced by suitable transverse frame members 13, such, 55 for instance, as those shown in Figs. 3 and 4.

Mounted on the frame members 12 are a plurality of transverse frame members 14, spaced from each other as illustrated in Fig. 1.

Mounted on the various frame members 14 are a plurality of transverse rows of brackets, the brackets of each row being indicated by the reference characters 15, 16, 17, 16^a and 18. These brackets are so arranged as to rotatably support rollers 17 and to make in general a channel-shaped or trough formation of the endless conveyer of which the rollers form a part.

At each end of the frame is a pair of long 70 rollers 20 and 21, the roller 20 being somewhat higher than the rollers 19 on which travel the three middle belts 22, and the roller 21 being somewhat higher than the roller 20 so as to cause the middle belts of 75 the endless conveyer to be elevated at the ends.

Traveling over the rollers 20 and 21, and also over the rollers 19, are a series of endless belts 22. A loose, flexible endless member of canvas or the like 23 extends around the endless conveyer members just described, the upper stretch of the member 23 resting on the belts 22 and the lower stretch having some slack as shown in Figs. 1 and 3.

Near what I shall call the front end of the machine, which is the right-hand end as shown in Fig. 1, are spaced uprights 24, at the upper ends of which are bearings 25 in which a shaft 26 is journaled. On the shaft 90 26, between the bearings 25, is a drum 27 from which project a large number of teeth or pins 28 of different lengths.

On the outer end of the shaft 26 is a belt pulley 29. On the shaft 26 is a pulley 30, 95 which is in line with a belt pulley on the shaft 31 on which one of the rollers 21 is mounted.

Near the discharge end of the machine are mounted sideboards or the like 34, as 100 shown in Fig. 1, to prevent the material being mixed from spilling over the sides of the conveyer near said discharge end. A suitable water pipe 35 is arranged to discharge water upon the material being fed to the 105 forward end of the mixing conveyer.

In the forms of my mixer shown in Figs. 5 and 6, the end rollers are not elevated above the other rollers of the trough, and the rollers 19^a are provided from end to end 5 of the trough, having belts 22^a similar to the rollers 19 and belts 22 as in Fig. 5, or straight end rollers 21^b are provided on a level with the lower rollers 19.

In the practical operation of my improved 10 clay mixing machine, the clay after having been crushed or otherwise reduced to comparatively small particles, is fed onto the endless belt 23 at the forward end of the machine, and is there thoroughly mixed with 15 water from the pipe 35. The water flow may be controlled by the valve 36. Power may be imparted to the pulley 29 in any suitable way.

It will be seen that when the shaft 26 is 20 rotated from the pulley 29, the drum 27 will be rotated for causing the pins 28 to strike, agitate and mix the material being operated upon.

On the belt pulley 30 and the belt pulley 25 on the shaft 31 is a belt 37 through which power may be transmitted to the shaft 31 and the forward roller 21. It will be seen that by thus imparting power to the forward roller 21^a, the lower stretches of the belts 22 30 will be drawn taut, while the upper stretches thereof, as well as the upper stretch of the endless belt 23, will be loose and will tend to sag down between the successive rows or series of rollers 19.

35 Thus the material being drawn along through the trough-like conveyer will be agitated as it rolls over the rollers 19 and then into the low places in the flexible endless conveyer members between the successive 40 rows of rollers 19. The arrangement of the rollers 19 is such as to give the endless conveyer the shape of a trough or channel so that the clay will not be discharged at the sides of the endless conveyer. When 45 the clay reaches the discharge end of the conveyer and starts to pass over the rearward rollers 20 and 21, the side-boards 34 will prevent the clay from being spilled over the sides of the conveyer.

50 It will be seen that my device is of very simple construction, and yet affords the advantage of an endless conveyer, which, in carrying the material from one end of the conveyer to the other, will serve to continually and thoroughly agitate and mix the material.

Some changes may be made in the construction and arrangement of the various parts of my improved device, without departing from the essential features and purposes of my invention, and it is my intention 60 to cover by my claims, any modified forms

of structure or use of mechanical equivalents which may be included within their scope.

I claim as my invention:

1. In a mixing device, an endless conveyer having its central portion comprised of a plurality of rows of rotating members arranged with the rotating members at the ends of the row higher than those between the ends of said row, the respective rollers in the different rows being alined longitudinally of the conveyer and having belts thereon, and an endless flexible conveyer member mounted upon said belts. 70

2. In a mixing device, an endless conveyer having its central portion comprised of a plurality of rows of rotating members arranged with the rotating members of the side rows higher than those between the side 80 rows, rollers adjacent to the ends of said conveyer, arranged higher than those rollers between the ends of the conveyer and between the side rows, endless belts mounted on said rows of rollers, an endless flexible 85 conveyer member mounted upon said belts, and means for imparting rotation to the end roller at the receiving end of the machine, whereby material on the conveyer will force the flexible conveyer member downwardly 90 between said rows, for causing said material to be agitated as it passes over the rollers.

3. In a mixing device, an endless conveyer, a plurality of rows of rotating members arranged with the rotating members at the sides higher than those spaced from and between the side rows, rollers adjacent to the ends of said conveyer, arranged higher than those rollers between the side rows and between the ends of the conveyer above 100 described, endless belts mounted on said rollers, an endless flexible conveyer member mounted upon said belts, and material retaining means at the sides of said endless conveyer at the discharge end of the machine. 105

4. In a mixing device, an endless conveyer having a plurality of rows of rotating members arranged with the rotating members of the side rows higher than those between the side rows and spaced from the ends of the conveyer, rollers adjacent to the ends of said conveyer, arranged higher than those rollers between the end rollers above described, endless belts mounted upon said rollers, an endless flexible conveyer member mounted upon said belts, means for imparting rotation to the end roller at the receiving end of the machine, and an agitating device arranged to agitate material on the 115 conveyer near the receiving end thereof. 120

Des Moines, Iowa, June 12, 1918.

HALVER RUFUS STRAIGHT.
